ATTORNEY

UNITED STATES PATENT OFFICE.

EDGAR L. BROWNE, OF CLEVELAND, OHIO.

DESIGN FOR AN ADVERTISING-CABINET.

SPECIFICATION forming part of Design No. 33,283, dated October 16, 1900.

Application filed September 12, 1900. Serial No. 29,812. Term of patent 3½ years.

To all whom it may concern:

Be it known that I, EDGAR L. BROWNE, a citizen of the United States, and a resident of Cleveland, in the county of Cuyahoga and State of Ohio, have invented and produced a new and original Design for an Advertising-Cabinet, of which the following is a specification, reference being had to the accompanying drawing, forming a part thereof.

10 The drawing is a front elevation of an advertising-cabinet, showing my new design. My said new design comprises, primarily, a quadrangular main holder, within which a lesser quadrangular holder is arranged. The 15 space intervening between the boundary-lines of the main holder is divided into horizontal strips, so as to form at each side of the lesser holder a row of substantially-square panels extending from the bottom boundary-line of said lesser holder upward to the top boundary-line of the main holder. The space between the top boundary-line of the lesser holder and the top boundary-line of the main holder is divided by vertical strips into panels, all of which are quadrangular in outline 20 save the central one, which is rectangular in outline. The space intervening between the lower boundary-line of the lesser holder, the lower boundary line of the main holder, and 25 the lower boundary-line of the panels arranged at the sides of said lesser holder is divided by vertical strips into panels, all of which are substantially quadrangular in out-

line save the central one, which is rectangular in outline. The lesser holder is divided 35 by vertical and horizontal strips into a general Maltese-cross figure, and the latter is divided by vertical and horizontal strips into substantially quadrangular panels, certain of which form a lesser Maltese-cross figure, 40 the central panel of which contains the figure of a star and the panels occupying each an angle of the lesser Maltese-cross figure containing each the figure of a flag. The series of panels adjoining one each of the panels occupying the angles of the lesser Maltese-cross figure contain each an oval figure for the display of likenesses or pictorial representations.

The cabinet further comprises rectangular 45 holders arranged obliquely to and one at each side of the main holder and each divided by horizontal strips into a continuous row of vertical substantially-quadrangular panels.

The main holder is surmounted by a final 50 ornamental fixture, as shown.

Having thus described my invention, I claim and desire to secure by Letters Patent—

The design for an advertising-cabinet substantially as herein shown and described.

EDGAR L. BROWNE.
